COMBINED STYLUS ARM AND STYLUS FOR A GRAMOPHONE PICKUP

Robert Sydney Spence, St. Margarets, Stanstead Abbots, near Ware, and Merton Minton, London, England, assignors to Cosmocard Limited, Waltham Cross, England, a British company

Application February 7, 1957, Serial No. 44,791

Claims priority, application Great Britain
November 8, 1956

Term of patent 14 years

(Cl. D26—14)

FIG. 1.

FIG. 2.

FIG. 3.

FIG. 4.

FIG. 5.

Fig. 1 is a side elevational view of a combined stylus arm and stylus for a gramophone pickup, showing our new design, the opposite side being substantially a mirror image thereof;

Fig. 2 is a perspective view;

Fig. 3 is a front elevational view;

Fig. 4 is a rear elevational view; and

Fig. 5 is a bottom plan view thereof.

We claim:

The ornamental design for a combined stylus arm and stylus for a gramophone pickup, as shown and described.
